PACKAGE SIZE INDICATOR FOR
WINDING MACHINESJohn O. McKean, Westfield, Mass., assignor to
Foster Machine Company, Westfield, Mass., a
corporation of Massachusetts

Application April 14, 1933, Serial No. 666,103

2 Claims. (Cl. 116—114)

One object of my invention is to provide a package size indicator for winding machines which is simple in construction, accurate in operation and adjustable to different sized packages.

Another object is to indicate visually that the package is approaching a predetermined size, so that it may be removed, if so desired, upon the exhaustion of a supply bobbin or the breaking of the yarn, thereby increasing the efficiency of the winding machine by decreasing the average number of stops per package wound.

Still another object is the construction of such a device having a weight and form such that it will not make a groove in the package or injure the threads wound thereon at its point of contact.

Other objects and advantages will be apparent as my invention is further described.

A practical embodiment of my invention is represented in the accompanying drawing, in which

Fig. 1 represents an elevation of a winding head and driving roll taken in a plane perpendicular to said driving roll and with the full sized package indicated by dotted lines;

Fig. 2 represents a transverse elevation of that portion of Fig. 1 which shows my invention, the full sized package again being denoted by dotted lines; and

Fig. 3 represents a detail transverse section taken in the plane of the line III—III of Fig. 1, looking in the direction of the arrows.

1 denotes a driving roll, mounted and driven in a manner well known in the art, and driving the package 2 by means of frictional contact therewith. Said package 2 is mounted on spindle 3 rotatably mounted on arm 4 which is held by means of bolt 5 in socket 6 which is pivotally mounted on shaft 7 journaled in a well known manner not here indicated. Attached to arm 4 is weight 8 held in place thereon by bolt 9 and having an upstanding portion 10 adapted to receive bolt 11 by which is adjustably attached thereto the supporting member 12 of the package size indicator, said member containing longitudinal slot 13 whereby it may be adjusted to different distances from the spindle 3. One straight side of said member 12 abuts a ledge 14 formed on upstanding portion 10 limiting the adjustment to that of a lineal nature and providing a convenient surface upon which to inscribe a scale (not shown) enabling a quick and accurate determination of the proper adjustment required to make a package of a given diameter.

At the outer end of supporting member 12 is an offset portion having two upstanding ears 15 so positioned as to be substantially equidistant from a vertical plane taken through the full package. Through said ears 15 is riveted a pivot 16 about which is pivotally attached a package contactor 17 comprising a strip of light and thin, yet wear-resistant sheet material having a spoon-shaped portion 18 formed in its free end. The smoothly formed bowl portion of said spoon is so positioned as to contact with the surface of a package upon its reaching a predetermined diameter.

Integral with supporting member 12 and intermediate ears 15 is a projecting abutment 19 adapted to support the package contactor 17 in an approximately horizontal position when the spoon-shaped portion of said contactor is not in contact with a package.

In operation, if it is desired to not employ my package size indicator, the package contactor is simply swung about its pivot to an inoperative position, as shown in dotted lines in Fig. 3. If it is desired to use the indicator, the package contactor is swung over to its operative position and comes to rest against the stop 19 which holds it approximately at right angles to its support. Thereupon, the supporting member is adjusted by means of the bolt and slot arrangement, so that the spoon portion will be a predetermined distance away from the winding spindle. Thereupon, the yarn is started on the spindle, the spindle is swung down so as to contact with the driving roll, and the winding thereupon proceeds in a well known manner until the size of the package approximates the size desired, for instance, such a size as is shown in the drawing. At this time the irregular surface of the package will contact with the spoon-shaped portion of my contactor, and will cause it to jiggle up and down violently, calling the attention of the operator to the fact that the package is of a sufficient size, so that upon the emptying of a supply bobbin, the package may be removed and a new one begun. Moreover, in case the winding is interrupted by a breaking of the yarn, an operator is enabled to judge by glancing at my indicator whether or not a new package should be begun.

Heretofore, there have been stop motions which mechanically stopped the winding of a package upon its reaching a predetermined size, whereupon the yarn was broken and a new package was begun even though there might only have been a fraction of a supply bobbin remaining to be wound. When such a fraction had been

wound on a new spindle, the stop motion stopped the package again in order that a new supply bobbin might be furnished. Moreover, in using such a stop motion, advantage would not ordinarily be taken of a break in the yarn when the package was approaching its proper size to remove the package and begin a new one. In view of the fact that the yarn is commonly marketed by weight, there is no disadvantage in winding packages of slightly different diameters, and with an invention such as I have described herein, the package may be permitted to wind even after it has grown to such a size that it contacts with the spoon-shaped portion of my package size indicator, thereby permitting an operator to finish winding a supply bobbin or to take advantage of a broken yarn to remove the package and start another.

The irregularities on the package surface are sufficient to impart to the spoon-shaped portion of my indicator an appreciable motion amply sufficient to attract an operator's attention. The smooth under-surface of my spoon-shaped portion and the lightness of my package contactor result in the fact that the threads are neither weakened nor cut by their contact therewith.

It is evident that various changes may be resorted to in the construction, form and arrangement of the several parts without departing from the spirit and scope of my invention, and hence I do not intend to be limited to the particular embodiment herein shown and described, but what I claim is:

1. In a winding machine, a winding spindle carrying rock arm provided with a ledge, and a package size indicator comprising a support adjustable in a linear direction only and adapted to abut said ledge, and a package contacting means pivoted to said support.

2. In a winding machine, a rock arm, a winding spindle carried thereby and arranged to support a package during the formation thereof, an adjustable support provided with a stop on said rock arm, and a strip of sheet metal pivoted to said support, said stop being adapted to keep said strip out of contact with the package until the package reaches a predetermined size, said strip being provided with a spoon-shaped recess in its free end, a wall of said recess being arranged to engage the package when the package attains a predetermined size.

JOHN O. McKEAN.
